2,398,256

SEWING AND KNITTING CABINET

Edward P. Schreyer, Milwaukee, Wis.

Application August 2, 1943, Serial No. 497,047

1 Claim. (Cl. 223—106)

This invention relates to improvements in sewing and knitting cabinets.

It is a general object of the present invention to provide an upright, hinged type of sewing and knitting cabinet which can be folded into compact form when not in use, and which will, nevertheless, when in closed condition, readily accommodate the various necessary articles of the seamstress or knitter.

A further object of the invention is to provide an article of the class described having a pair of relatively foldable upright members provided on their inner sides with shelves which face toward one another, the shelf on one of said foldable members being equipped with spool receiving spindles which are so positioned with respect to similar spindles on the other foldable member that large spools or balls of thread on the spindles of one shelf will compactly interfit with smaller spools on the set of spindles of the opposite shelf when the cabinet is closed.

A further object of the invention is to provide a cabinet of the class described so hinged together and constructed as to provide a maximum of useful space between the foldable members when the cabinet is closed while preserving a neat closed appearance. Thus, a flexible sewing or knitting bag supported on one of the foldable cabinet members may be suitably accommodated, while in suspended position, between the members when the cabinet is closed, even when a portion of said bag is filled with bulging articles.

A further object of the invention is to provide a sewing or knitting cabinet which is so constructed that it may serve as an adjustable holder for a skein of yarn while the knitter is winding said yarn in the form of a ball.

Other objects of the invention are to provide a sewing and knitting cabinet which is neat and attractive in appearance, to serve as a fireplace screen or other permanent article of furniture when not in use; which is light in weight so that it can be readily moved from one room to another; which is relatively inexpensive to manufacture; and which is well adapted for the purposes described.

With the above and other objects in view the invention consists of the improved sewing and knitting cabinet, and all its parts and combinations as set forth in the claim, and all equivalents thereof.

In the accompanying drawing illustrating one complete embodiment of the preferred form of invention, in which the same reference numerals designate the same parts in all of the views:

Fig. 1 is a perspective view of the cabinet in closed condition;

Fig. 2 is a perspective view of the cabinet in open condition looking at the interior thereof;

Fig. 3 is a longitudinal vertical sectional view through the cabinet taken approximately on the line 3—3 of Fig. 1, parts of the lower legs being broken off; and

Fig. 4 is a top view of the cabinet in closed condition.

Referring more particularly to the drawing the numerals 5 and 6 designate generally a pair of upright members which are hinged together as at 7 so that the upright members may be moved relative to one another on the hinges from the closed position of Fig. 1 to the open position of Fig. 2.

The upright member 5 includes upright side strips 8 and 9 which are spaced apart by transverse members 10 and 11. The members 8, 9, 10 and 11 are all grooved as at 12 (Fig. 3) to receive the edges of a panel 13. Thus, the panel is securely held in position in a simple manner. The panel 13 may be formed of cardboard, composition board, plywood or other relatively thin material. It is to be noted that the panel is positioned relatively close to the outermost sides of the strips 8, 9, 10 and 11 so as to provide a maximum of space on the inner side of the panel 13 for accommodating articles. The other upright member 6 is constructed in a similar manner and comprises upright strips 14 and 15 which are spaced apart by transverse top and bottom strips 16 and 17. The upright member 6 also includes an outer panel 18 which is similar to the panel 13 and held in position in the same manner as heretofore described in connection with the panel 13.

The upright strips 8, 9, 14 and 15 project below the bottom transverse strips 11 and 17 to form supporting legs. The strips 8 and 14 also project a substantial distance above the top transverse members 10 and 16 as at 19 and 20 to form yarn holders. The upper ends of the upright strips 9 and 15 may also project upwardly a similar distance to match the appearance of the yarn holding extensions 19 and 20.

Spaced downwardly from the upper rails 10 and 16 are shelves 21 and 22. These shelves are positioned against the inner surfaces of the panels 13 and 18 and project a substantial distance beyond the upright strips 8, 9, 14 and 15 as at 23 and 24. When the cabinet is in the closed condition of Fig. 3 the adjacent edges of the shelves 21 and 22 contact one another, as shown in Fig.

3, and hold the two upright members 5 and 6 in a relatively widely spaced condition so as to accommodate a maximum number of articles between the foldable members. It is to be noted that the hinges 7 are so constructed as to permit this relatively wide spacing in closed condition. To this end, each hinge leaf may have a pair of angularly disposed wings, as shown in Fig. 4, the outer of which is attached to the upright strips 9 and 10, the inner or pintle carrying wing of each plate extending obliquely, as shown.

The shelf 21 is equipped with spindles 25 which project upwardly therefrom. These spindles are staggered in position with respect to similar spindles 26 on the opposite shelf 22. With this arrangement, when the cabinet is closed as in Fig. 4, large balls 27 of mending cotton may be positioned on the spindles of one of the shelves and smaller spools 28 may be positioned on the spindles 26 of the other shelf. Due to the staggered position of the spindles the spools and balls of thread on the two sides will interfit, as shown in Fig. 4, to permit closing of the cabinet without interference.

Spaced below the shelf 22 is another shelf 29 which is of less depth than the shelf 22 and which has spindles 30 for accommodating standard sized spools. Mounted on the upright member 5 opposite to the shelf 29 is a reinforcing strip 31. It is to be noted that when the cabinet is closed, as in Fig. 3, there is a substantial space between the shelf 29 and the strip 31.

A fabric panel 33 provided with article receiving pockets 34 may be secured between the shelf 29 and the bottom transverse member 17. On the opposite side of the cabinet the shelf 21 may be equipped with end pegs 35 for removably holding a knitting or sewing bag 36 and a pin cushion 37. When the cabinet is closed, as shown in Fig. 3, the bag 36 may bulge into the spaces below the shelves 21 and 22 and into the space below the transverse strip 31 while extending downwardly through the space 32 between the shelf 29 and the strip 31. Thus the bag may be accommodated, while holding a reasonable number of articles, without interfering with the complete closing of the cabinet. This bag may be readily removed from the cabinet when desired, for use independently thereof.

Yarn is commonly sold in elongated skeins which the knitter usually wishes to wind in a ball before using the yarn for knitting purposes. The present sewing cabinet provides a unique holder for the skein while the yarn is being unwound therefrom. The skein of yarn 38 may be placed over the yarn holding projections 19 and 20 and the cabinet may be opened a desired distance depending upon the length of the skein.

Thus an adjustable yarn holder is provided without detracting from the appearance of the sewing cabinet.

The cabinet may be equipped with handles 39 so that it can be easily moved from one location to another. When the cabinet is not in use for sewing, it may be opened out to the position of Fig. 2 and used as an ornamental fireplace screen with the outer sides of the panels 13 and 18 facing toward the room. These panels may be attractively decorated as desired.

It is apparent that the construction is such that a maximum number of useful articles may be accommodated in a relatively thin cabinet, when the cabinet is closed, without interfering with the complete closing movement. It is also apparent that the particular hinging and shelf arrangement provides a maximum amount of useful space in the position of Fig. 3 including space within which a sewing or knitting bag may be suspended.

Various changes and modifications may be made without departing from the spirit of the invention and all of such changes are contemplated as may come within the scope of the claim.

What I claim is:

A sewing and knitting cabinet comprising a pair of upright frame members hingedly connected to each other at adjacent upright edges, each frame member including edge strips and a relatively thin panel positioned toward the outer faces of said edge strips to provide an article accommodating space on the inner side of the panel and within the edge strips, a transverse article shelf in the upper portion of the article accommodating space of each frame member, said shelves having outer edges which project beyond the inner faces of the edge strips and abut when the cabinet is closed to maintain the inner faces of the edge strips in spaced position, the hinge connection for the frame members including hinges having extensions of such length as to permit said spacing produced by the abutting shelves while maintaining the frame members in substantial parallelism when the cabinet is closed, means on one of said shelves from which a flexible bag may be suspended to bulge into the article accommodating spaced therebelow and into the space between the frame members when the cabinet is closed, and a transverse shelf in each frame member below the first mentioned shelves, said second shelves being of less width than the shelves thereabove so that the edges of said lower shelves are spaced apart when the cabinet is closed whereby said bag may hang downwardly through the space between said lower shelves.

EDWARD P. SCHREYER.
